Inventor:

Henry Howard
By his Attorney
Sidney Landau

United States Patent Office.

HENRY HOWARD, OF SPRINGFIELD, MASSACHUSETTS.

Letters Patent No. 78,454, dated June 2, 1868.

IMPROVEMENT IN VALVE-GEAR FOR STEAM-HEATING APPARATUS.

The Schedule referred to in these Letters Patent and making part of the same.

TO ALL WHOM IT MAY CONCERN:

Be it known that I, HENRY HOWARD, of Springfield, in the county of Hampden, and State of Massachusetts, have made and invented a new and useful Combination-Valve for Steam-Heating Apparatus; and I do hereby declare that the following is a full, clear, and exact description of the construction and operation of the same; reference being had to the annexed drawings, making a part of this specification, in which—

Figure 1 is an end elevation.

Figure 2, a side elevation.

Figure 3, a horizontal section through the plane $w-x$.

Figure 4, a vertical section through the plane $y-z$.

Figure 5, a perspective view of valve and stem.

Figure 6, a bottom elevation of the valve-seat nut.

Figure 7, a top elevation of the hand-wheel; and

Figure 8, a top elevation of the connection-bar.

My invention relates to the induction and eduction-valves of steam-heating apparatus; the induction-valve being that through which the steam enters the radiators, coils, or other apparatus constituting the heater, and the eduction that through which the water of such steam, when condensed, leaves the heater, and finds its way back to the boiler.

Heretofore, so far as my knowledge extends, the induction and eduction-valves of such heating-apparatus have been arranged separately, and without mechanical connection, whereby each of such valves is operated independently of the other; but in all such apparatus such valves should be opened and closed nearly or quite simultaneously. This is not only a matter of convenience and economy, but if the induction-valve be opened while the eduction is closed, the steam admitted condenses; and the resulting water, having no outlet, remains and cools in the heater. Again, if the eduction-valve is opened while the induction is closed, any considerable pressure of steam in the boiler forces water therefrom up into the heater, where it also remains and cools.

Now, it often happens that one valve is opened or closed, as above indicated, without reference to the other, and in either case, when the valves are again properly opened, and steam let into the heater, it comes in contact with the cool water therein, and produces that loud, snapping noise, not unfrequently heard, and other unpleasant, if not dangerous consequences.

My invention, which is intended to overcome these objections, consists in the combination and arrangement of the induction and eduction-valves in one case, so that both valves are opened and closed simultaneously, and by the same machinery.

I have also made certain improvements in the valve-stems and valve-seat nuts, for the purpose of making the device steam-tight, and further, to facilitate the egress of water from the heater during the ingress of steam, I provide the screw-threaded pipe connecting the double-valve case and heater with a partition, and of that part of the pipe thus partitioned off, which communicates with the induction-valve, I make an extension, some inch or more beyond the other half.

In carrying out my invention, I construct a double-valve case, F, forming therein two round openings, extending through the same, and provide each end of such openings with a female screw at the top, for the insertion of the valve-seat nuts $c c'$, and the bottom $k k'$, for the insertion of the ordinary pipes leading to and from the boiler.

I also construct and provide the double case F with a short screw-threaded pipe, G, which pipe is to be screwed into a socket on the heater, whereby the valves and heater are connected.

From case F, extending through pipe G, and keeping ports $h h'$ quite separate, I provide a partition, H, and make an extension, I, of such partition, and that part of pipe G communicating with port h' , fig. 8, for the purpose of better conducting water from the heater during the ingress of steam.

And further, I construct round, bevelled valves $g g'$, providing the same with stems $e e'$, and providing such stems with conical enlargements $f f'$, fig. 5.

I also construct valve-seat nuts $c c'$, as seen in fig. 4, with a screw-thread at either end, and a thin ring of metal separating such threads.

Through the centre of nuts $c c'$ there is a round opening, barely sufficient for the passage of the stems $e e'$, and at the bottom of the nuts I enlarge such opening in a conical form, $d d'$, to correspond with the conical enlargements $f f'$.

The tops of nuts $c c'$ are concave, as seen at $s s'$, and in such concavity I place a cotton-wicking, or other suitable packing, over which I screw the ordinary packing-nuts $b b'$.

The stems $e e'$ are connected at the top by a bar, D, and thus secured by nuts $a a'$.

I also provide an operating-screw, E, which enters case F, and passes up through bar D.

Around the stem of screw E, and above bar D, I place a ferrule, C, and hand-wheel B, which latter is secured by the screw A.

I connect the several parts in the following order: screw E, bar D, ferrule C, wheel B, and screw A. I then insert valves $g g'$ in their cases, closing the tops thereof with seat-nuts $c c'$, and packing-nuts $b b'$. I then insert screw E in case F, and connect stems $e e'$ by the bar D and nuts $a a'$.

Thus constructed and arranged, it is obvious that by turning wheel B, valves $g g'$ are operated simultaneously; their ports $h h'$ are opened and closed by the same operation, and that by turning screw E the enlargements $f f'$ are drawn up into the conical openings $d d'$, thus making the top of the valve-cases steam-tight, when ports $h h'$ are open for the admission of steam into the heater.

It is also obvious that in the application of my combination-valve to coils or coil-heaters, both ends of the pipes forming such heaters must be brought around nearly together, and entered in the same socket into which is screwed pipe G.

Having thus described the construction and operation of my invention, what I claim therein as new, and desire to secure by Letters Patent, is—

1. The double case F, in combination with valves $g g'$, substantially as herein set forth.
2. The partitioned pipe G, formed on the double-valve case F, as herein specified.
3. The prolongation I, formed on pipe G, as herein specified.
4. The valve g and stem e , in combination with the valve g' and stem e' , bar D, screw E, and case F, substantially as herein specified.

HENRY HOWARD.
